UNITED STATES PATENT OFFICE

91,230

DESIGN FOR A COMBINED NECKTIE RACK AND SUPPORT THEREFOR

Joseph Carlton Bagnall, Attleboro, Mass., assignor to The Baer & Wilde Co., Inc., a corporation of Massachusetts

Application June 20, 1933. Serial No. 48,470

Term of patent 3½ years

To all whom it may concern:

Be it known that I, JOSEPH CARLTON BAGNALL, a citizen of the United States of America, residing in Attleboro, county of Bristol, State of Massachusetts, have invented a new, original, and ornamental Design for a Combined Necktie Rack and Support Therefor, of which the following is a specification, reference being had to the accompanying drawing forming a part thereof.

Fig. 1 is a front elevation of a combined necktie rack and support therefor, showing my new design; and Fig. 2 is a top plan view of the same.

I claim:

The ornamental design for a combined necktie rack and support therefor, substantially as shown.

JOSEPH CARLTON BAGNALL.
